TOBACCO CUTTING MACHINE

Walter Everett Molins, Deptford, London,
EnglandApplication September 28, 1931, Serial No.
565,625, and in Great Britain October 3, 1930

5 Claims. (Cl. 146—112)

This invention relates to tobacco cutting machines of the rotary type, and has for its object to provide improved means for feeding and cutting tobacco to secure cut material of uniform quality and length.

5 In tobacco cutting machines, the leaves are compressed into a solid mass usually termed a "cheese" and fed through an orifice across which a knife is moved to cut off a slice from the "cheese".

10 Usually the tobacco is fed through the orifice by means of rotating fluted rollers or the like, a common arrangement being a large roller either fluted or plain, beneath the tobacco mass and several small fluted rollers above the tobacco.

15 Formerly, the large roller was made of wood with a plain rim and the tobacco was cut by a reciprocating knife which cut slightly into the surface of the wood at each stroke.

20 Owing to the rapid wear of the wooden roller and the passage of uncut tobacco, as holes were formed in the surface of the roller by nails and similar hard objects in the tobacco, a metal roller was subsequently used.

25 As it is impossible to cut on to the surface of a metal roller, it became necessary to feed the tobacco through a rectangular mouthpiece across which the knife could move and give the knife sufficient movement to pass slightly below the mouthpiece to obtain a clean cut. The lower lip of the mouthpiece formed an obstacle to the feeding of the tobacco which was pushed through the mouth piece by endwise pressure from the succeeding mass of tobacco forced between the fluted rollers, and the resulting "cheese" was not always fed uniformly. Moreover, the leaf is fed and packed by hand into the machine and as the corners are naturally more difficult to pack snugly than the centre of the "cheese", the density at the 30 corners was usually less than in the middle, and a quantity of uncut or irregularly cut tobacco was removed from the lower corners of the "cheese".

35 The present invention comprises a rotary tobacco cutting machine in which tobacco leaves are compressed and fed through a mouthpiece, characterized by a rotatable cutting blade being arranged to sweep across the said mouthpiece in such a manner that the edge of the cutting blade engages with a feeding roller having a rim of concave section which corresponds to the path of the cutting blade and which forms the wall of the mouthpiece remote from the axis of rotation of the knife.

40 55 The invention will be more particularly de-

scribed with reference to the accompanying drawing, in which:

Fig. 1 is a section of a tobacco cutting machine constructed according to the invention.

Fig. 2 is a view of Fig. 1 in the direction of the arrow "A".

Fig. 3 is an enlarged view of a portion of the front of the machine showing the mouthpiece and one cutting knife.

Fig. 4 is a similar view to Fig. 3 showing a modified form of mouthpiece.

Referring to the drawing which shows a tobacco cutting machine having two blades, the blades 1 are mounted on a rotatable member or carrier 2 in such a manner that they project through the inner face of the carrier at an angle as shown in Fig. 1.

The blades are carried in slides 3, and have means of the kind described in British specification No. 24236/30 for automatically feeding them forward, but which have been omitted from the drawing, and are ground by an emery wheel 34.

The tobacco in the form of leaves is laid upon a belt 4 moving in the direction of the arrow; the belt running at the bottom of a box or trough formed by boards 5.

A large roller 6 is mounted as shown in Fig. 1 and receives the tobacco leaves from the belt. A series of fluted rollers 7, 8, 9 and 10 co-operate with the belt 4 and roller 6 and feed the tobacco leaves through the mouthpiece 11 compressing them during this movement into a solid "cheese". The large roller 6 is preferably made of metal and has a plain rim of concave section, as shown in Figs. 2, 3 and 4, and the blade 2 is so arranged that the corner 2^a thereof contacts with the concave rim as the blade passes across the "cheese". In Figs. 3 and 4 the path of the corner of the blade is shown by a broken line; this line does not coincide with the rim in those views because the blade rotates in a plane in advance of that of the spindle of roller 6 (see Fig. 1).

It will be observed that the extreme corner of the blade which contacts with the roller, and which actually performs no cutting operation, is liable to become blunt, but this is of no consequence as the leading and cutting edge of the blade is always kept sharp by contact with the grinding wheel during each revolution of the carrier 2.

Owing to the fact that the concave surface of the roller 6 forms the bottom of the mouthpiece, the feed of the tobacco is unobstructed, and regular across the entire section of the mouth, and the resulting "cheese" is of uniform density

throughout, this effect being further secured by the depth of the edges of the "cheese" being less than that of the centre which tends to keep these portions as well compressed as the centre.

5 In some circumstances, however, it may be desirable to form the upper surface of the mouthpiece of convex section as shown in Fig. 4.

It is therefore possible to cut a uniform slice from the entire surface of the "cheese", and a 10 machine constructed according to the invention has all the advantages of high speed and smooth running resulting from the rotary movement, combined with the best cutting results.

What I claim as my invention and desire to 15 secure by Letters Patent is:—

1. In a tobacco cutting machine, the combination with a rotating cutter, of a mouthpiece co-operating with said cutter, and means for feeding tobacco to said mouthpiece, said mouthpiece 20 comprising a stationary member defining that portion of the mouthpiece adjacent the axis of rotation of said cutter and slidably contacted by said cutter and a rotatable member defining that portion of the mouthpiece remote from the axis 25 of rotation of said cutter, said rotatable member having a peripheral portion of concave shape conforming substantially to the path of movement of the outermost portion of said cutter.

2. In a tobacco cutting machine the combination 30 with a rotating cutter, of a roller rotatable about an axis transverse to the axis of rotation of said cutter, said roller having a concave periphery conforming substantially to and co-operating with the outer portion of said cutter; a 35 stationary member positioned in close proximity to the path of movement of said cutter and forming with said roller a mouthpiece through which tobacco may be fed, said stationary member being slidably contacted by said cutter, and means 40 for feeding tobacco through said mouthpiece.

3. In a tobacco cutting machine the combination 45 with a rotating cutter, of a roller rotatable about an axis transverse to the axis of rotation of

said cutter, said roller having a concave periphery conforming substantially to and cooperating with the outer portion of said cutter, a stationary member positioned in close proximity to the path of movement of said cutter and forming with said roller a mouthpiece through which tobacco may be fed, said stationary member being slidably contacted by said cutter, and means including rollers located adjacent and cooperating with said first named roller for feeding tobacco through said mouthpiece.

4. In a tobacco cutting machine, the combination 50 with a rotating cutter, of a mouthpiece co-operating with said cutter, and means for feeding tobacco to said mouthpiece, said mouthpiece comprising a stationary member defining that portion of the mouthpiece adjacent the axis of rotation of said cutter and slidably contacted by said cutter and a rotatable member defining that portion of the mouthpiece remote from the axis 55 of rotation of said cutter, said rotatable member having a peripheral portion of concave shape conforming substantially to the path of movement of the outermost portion of said cutter, said stationary member having such configuration that the mouthpiece is of greatest depth adjacent the central portion thereof.

5. In a tobacco cutting machine, the combination 60 with a rotating cutter, of a mouthpiece co-operating with said cutter, and means for feeding tobacco to said mouthpiece, said mouthpiece comprising a stationary member defining that portion of the mouthpiece adjacent the axis of rotation of said cutter and a rotatable member defining that portion of the mouthpiece remote from the axis 65 of rotation of said cutter, said rotatable member having a peripheral portion of concave shape conforming substantially to the path of movement of the outermost portion of said cutter, said stationary member being convexly formed to provide a mouthpiece of substantially uniform depth.
